PLUG-IN GUITAR TRANSMITTER HOUSING

Jack C. Roberts, Los Angeles County, Calif., assignor to
Saxton Electronics Corporation, Congers, N.Y., a corporation of New York

Filed Feb. 7, 1968, Ser. No. 10,482

Term of patent 14 years

(Cl. D26—14)

FIGURE 1 is a perspective view showing my new design for a plug-in guitar transmitter housing in accordance with the present invention;

FIGURE 2 is a side elevational view thereof;

FIGURE 3 is a top plan view thereof; and

FIGURE 4 is a bottom plan view thereof.

I claim:

The ornamental design for a plug-in guitar transmitter housing, substantially as shown and described.
